DESIGN FOR A WATCH CASE

Maurice B. Peikin, New York, N. Y.

Application February 9, 1946, Serial No. 126,415

Term of patent 14 years

(Cl. D42—8)

To all whom it may concern:

Be it known that I, Maurice B. Peikin, a citizen of the United States, residing at New York, in the county of New York and State of New York, have invented a new, original, and ornamental Design for Watch Cases, of which the following is a specification, reference being had to the accompanying drawing, forming part thereof.

Fig. 1 is a front elevation of a watch case, show-

ing my new design, black markings being shown in full black and red markings being indicated as red by conventional hatching;

Fig. 2 is an edge elevational view; and

Fig. 3 is a rear elevational view of the same.

I claim:

The ornamental design for a watch case, as shown and described.

MAURICE B. PEIKIN.
